His Attorney.

UNITED STATES PATENT OFFICE

2,335,660

ANTIPUMP CONTROL OF ELECTRIC SWITCHES

Junius P. Fraps, Yeadon, Pa., assignor to General Electric Company, a corporation of New York

Application October 22, 1942, Serial No. 462,895

7 Claims. (Cl. 175—294)

My invention relates to improvements in the control of electric switches and more particularly trip free circuit breakers which are opened automatically on the occurrence of abnormal circuit conditions and which are arranged to be closed in response to the closing operation of a control switch to effect the energization of the circuit breaker closing means.

If the control switch is left in its circuit closing position after the circuit breaker closes and the circuit breaker immediately opens due to an abnormal condition on the circuit it controls, the closing means of the circuit breaker must not again be energized as soon as the circuit breaker reaches its open position. Otherwise, the circuit breaker will be reclosed on the abnormal condition. In other words, the circuit breaker will continue to open and close rapidly while the abnormal condition lasts and the control switch remains closed. This so-called pumping action, if allowed to continue, is liable to result in serious damage to the circuit breaker and other connected apparatus.

An object of my invention is to provide an improved control arrangement for preventing the repeated opening and closing of a circuit breaker under the conditions mentioned. Another object of my invention is to provide an improved anti-pump control arrangement such that the desired opening and closing operations of the circuit breaker can be initiated by the actuation of a single throw stay-put type of control switch. A further object of my invention is to provide an improved anti-pump control arrangement whereby the closing of the circuit breaker may be effected by closing a stay-put type of control switch, and the opening of the circuit breaker may be effected by opening the control switch. These and other objects of my invention will appear in more detail hereinafter.

In accordance with my invention, I provide an auxiliary relay and a single throw stay-put control switch which is operative when closed while the circuit breaker is open to effect the energization of a control relay only when the auxiliary relay is deenergized, the control relay when energized being effective to energize the closing means of the circuit breaker. Further, I provide means for effecting the energization of the auxiliary relay when the circuit breaker closes while the control switch is closed and means independent of the opening of the circuit breaker for maintaining the auxiliary relay energized until the control switch is opened. Also, in accordance with my invention, I so arrange that the opening of

the control switch effects the deenergization of the auxiliary relay to cause the opening of the circuit breaker.

My invention will be better understood from the following description when considered in connection with the accompanying drawing, and its scope will be pointed out in the appended claims.

The single figure of the accompanying drawing diagrammatically illustrates an embodiment of my invention as applied to control the closing and opening of a circuit breaker 1, which for simplicity is shown single pole in a circuit comprising a conductor 2. It will, of course, be obvious that as far as my invention is concerned the number of poles in the circuit breaker is immaterial. As schematically shown, the circuit breaker is of the automatic trip free type and is provided with closing means 3, opening means 4 and tripping means 5, the last of which is responsive to abnormal circuit conditions to effect the opening of the circuit breaker. Also, as schematically shown, the closing, opening and tripping means are of the electromagnetic single-solenoid type comprising windings 6, 7 and 8, respectively, although it will be apparent to those skilled in the art that my invention is not limited to this particular type. As illustrated, the fault responsive tripping means 5 has its winding 8 connected in series in the circuit controlled by the circuit breaker 1 so as to respond to excess current conditions whereby to collapse the over-center circuit breaker holding toggle 9. Likewise, the opening means 4 is also arranged when energized to collapse the holding toggle 9. With the collapse of this toggle, the circuit breaker 1 is free to open under suitable bias such as furnished by a spring 10 since the overcenter operating toggle 11 can collapse downwardly when the restraint of the abutment 12 is removed by the collapse of the holding toggle 9. The circuit breaker 1 is also provided with a plurality of "a" auxiliary switches 13 and 14 which are closed when the circuit breaker is closed and opened when the circuit breaker is opened.

In accordance with my invention, I control the operation of the closing and opening means 3 and 4 by a control relay 15, an auxiliary relay 16 and a single throw stay-put type of control switch 17. The control relay 15 is operative when energized to effect the energization of the closing means 3. For this purpose, the control relay is provided with a set of "closed when energized" contacts 18, 19 in series relation in the energizing circuit 20 of the winding 6 of the closing means 3. The control switch 17 is operative when

closed while the circuit breaker 1 is open to effect the energization of the control relay 15 only when the auxiliary relay 16 is deenergized. For this purpose, the energizing circuit 21 of the winding 22 of the control relay 15 includes in series the control switch 17 and a set of "closed when deenergized" contacts 23, 24 of the auxiliary relay 16.

For effecting the energization of the auxiliary relay 16 when the circuit breaker 1 closes while the control switch 17 is closed, the energizing circuit 25 of the winding 26 of this relay includes in series relation the control switch 17 and the circuit breaker "a" auxiliary switch 13. Further in accordance with my invention, I provide means independent of the opening of the circuit breaker 1 for maintaining the auxiliary relay 26 energized until the control switch 17 is opened. As shown, this means includes the "closed when energized" set of auxiliary relay contacts 27, 28 which complete a seal-in circuit 29 in parallel with the "a" auxiliary switch 13.

Also in accordance with my invention, I provide means controlled by the control and auxiliary relays 15 and 16 for effecting the energization of the opening means 4 when the control switch 17 is opened while the circuit breaker 1 is closed. As shown, this means includes an energizing circuit 30 which includes in series relation the winding 7 of the opening means 4, the circuit breaker "a" auxiliary switch 14, a set of "closed when deenergized" contacts 31, 32 controlled by the control relay 15 and a set of "closed when deenergized" contacts 33, 34 of the auxiliary relay 16.

Assuming the circuit breaker 1 and the control switch 17 both closed and the circuit 2 normal, then the parts are positioned as shown in the drawing. The control relay 15 is deenergized since its circuit 21 is open at the contacts 23, 24 of the auxiliary relay 16. The auxiliary relay 16 is energized since its circuit is completed through the auxiliary switch 13 and also through the seal-in contacts 27, 28 in parallel. Assuming now an excess current condition on the circuit 2 such as to actuate the tripping means 5, then the circuit breaker 1 will be opened in consequence of the collapse of the holding toggle 9. The auxiliary relay 16, however, will not be deenergized since its energizing circuit remains completed through its seal-in contacts 27, 28. Consequently, the contacts 23 and 24 of the auxiliary relay 16 remain open. As long as these contacts are open, it is impossible to energize the control relay 15 and thereby the closing means 3. Therefore, no pumping action of the circuit breaker 1 can occur. In order to close the circuit breaker 1, the auxiliary relay 16 must be deenergized by opening the control switch 17. The auxiliary relay 16 then closes its contacts 23, 24 and 33, 34 and opens its contacts 27, 28. Closure of the control switch 17 is then effective to complete the circuit 21 of the winding 22 of the control relay 15. This relay then closes its contacts 18, 19 and completes the energizing circuit 29 of the closing means 3 whereby to effect the closing of the circuit breaker 1. As soon as the circuit breaker 1 closes its "a" auxiliary switch 13, the auxiliary relay 16 is energized to open its contacts 23, 24 and 33, 34 and close its seal-in contacts 27, 28, and the parts are again positioned as shown in the drawing.

If it is desired to open the circuit breaker 1 by opening means 4, then the control switch 17 is

opened. The opening of this switch deenergizes the auxiliary relay 16 which closes its contacts 33, 34 and thereby completes the energizing circuit 30 of the opening means 4 to effect the collapse of the holding toggle 9 and thereby the opening of the circuit breaker 1.

In order to effect the opening of the circuit breaker 1 independently of the control switch 17, the contacts 35, 36 of any switching device other than the control switch 17 are arranged in parallel with the serially related contacts 31, 32 of the control relay 15 and 33, 34 of the auxiliary relay 16. The contacts 35, 36 are normally open. When these contacts are closed while the circuit breaker is closed, then the circuit of the opening means 4 is completed by way of the conductors 37 and 38 independently of the control switch 17 and also the relays 15 and 16. With this arrangement, it will be noted that there is no change in the energizing circuit of the winding 26 of the auxiliary relay 16 since this circuit remains energized through the stay-put control switch 17. Consequently, following the opening of the circuit breaker 1 in consequence of the closing of the contacts 35, 36, the circuit breaker can again be closed only by opening and closing the control switch 17.

In order to open or to close the circuit breaker 1 by a device other than the control switch 17, I provide in series with the control switch 17 a switching device having cooperating contacts 39, 40 in series relation with the contacts of the control switch 17. With this arrangement, it will be noted that the closing operation of the circuit breaker 1 can be effected only when the control switch 17 is closed and the contacts 39, 40 are closed. However, the opening of either the control switch 17 or the contacts 38, 39 will effect the tripping of the circuit breaker.

While I have indicated the various control circuits as energized by direct current, it will be apparent to those skilled in the art that any dependable source of either direct or alternating current can be used. From the foregoing, it will be observed that I have provided a simple and effective means for controlling by a single throw stay-put control switch the opening and closing operations of an automatic trip free circuit breaker without any pumping action of the circuit breaker and the hazards consequent thereupon.

While I have shown and described my invention in considerable detail, I do not desire to be limited to the exact arrangements shown, but seek to cover in the appended claims all those modifications that fall within the true spirit and scope of my invention.

What I claim as new and desire to secure by Letters Patent of the United States is:

- 60 1. In an anti-pump control arrangement for an automatic trip free circuit breaker provided with closing means and opening means; means for controlling the energization of said closing and opening means comprising a control relay 65 operative when energized to effect the energization of said closing means, an auxiliary relay and a single throw stay-put control switch operative when closed while the circuit breaker is open to effect the energization of said control relay only 70 when the auxiliary relay is deenergized, means for effecting the energization of the auxiliary relay when the circuit breaker closes while the control switch is closed, means controlled by the auxiliary relay for maintaining itself energized independently of the opening of the circuit break-

er and until the control switch is opened and for effecting the energization of said opening means when both the control relay and the auxiliary relay are deenergized.

2. In an anti-pump control arrangement for an automatic trip free circuit breaker provided with closing means and opening means; means for controlling the energization of said closing and opening means comprising a control relay operative when energized to effect the energization of said closing means, an auxiliary relay, switching means controlled by said auxiliary relay and a single throw stay-put control switch operative when closed while the circuit breaker is open to effect the energization of said control relay only when the auxiliary relay is deenergized, switching means dependent on the closing of the circuit breaker for effecting the energization of the auxiliary relay when the circuit breaker closes while the control switch is closed, and switching means controlled by the auxiliary relay for maintaining itself energized independently of the opening of the circuit breaker and until the control switch is opened and for effecting the energization of said opening means when both the control relay and the auxiliary relay are deenergized.

3. In an anti-pump control arrangement for an automatic trip free circuit breaker provided with closing means and opening means; means for controlling the energization of said closing and opening means comprising a control relay operative when energized to effect the energization of said closing means, an auxiliary relay and a single throw stay-put control switch operative when closed while the circuit breaker is open to effect the energization of said control relay only when the auxiliary relay is deenergized, means for effecting the energization of the auxiliary relay when the circuit breaker closes while the control switch is closed, and means independent of the opening of the circuit breaker for maintaining the auxiliary relay energized until the control switch is opened and for effecting the energization of said opening means upon the opening of said control switch while the control relay is deenergized.

4. In an anti-pump control arrangement for an automatic trip free circuit breaker provided with closing means and opening means; means for controlling the energization of said closing and opening means comprising a control relay operative when energized to effect the energization of said closing means, an auxiliary relay and a single throw stay-put control switch operative when closed while the circuit breaker is open to effect the energization of said control relay only when the auxiliary relay is deenergized, means for effecting the energization of the auxiliary relay when the circuit breaker closes while the control switch is closed, means independent of the opening of the circuit breaker for maintaining the auxiliary relay energized until the control switch is opened, and means controlled by

said control and auxiliary relays for effecting the energization of said opening means when said control switch is opened while the circuit breaker is closed.

5. In an anti-pump control arrangement for an automatic trip free circuit breaker provided with electromagnetic closing means, electromagnetic openings means, fault responsive tripping means, and a plurality of "a" auxiliary switches; means for controlling the energization of said opening and closing means comprising a single throw stay-put control switch, a control relay having an energizing winding and two sets of contacts, one closed and the other open when the control relay is energized and vice versa, an auxiliary relay having an energizing winding and three sets of contacts, one closed and two open when the auxiliary relay is energized and vice versa, an energizing circuit for the winding of said control relay including in series said control switch and one set of open when energized contacts of said auxiliary relay, an energizing circuit for the winding of said closing means including the closed when energized contacts of the control relay, an energizing circuit for the winding of said auxiliary relay including in series said control switch and one of said circuit breaker auxiliary switches, a seal-in circuit for said auxiliary relay in parallel with said one of said auxiliary switches and including the closed when energized contacts of the auxiliary relay, and a circuit for said opening means including in series the winding thereof, another of said circuit breaker auxiliary switches, the closed when deenergized contacts of said control relay and the other of the open when energized contacts of the auxiliary relay.

6. An anti-pump control arrangement for an automatic trip free circuit breaker comprising a plurality of cooperating relay means, a single throw stay-put control switch, means controlled by said cooperating relay means and by said control switch when closed while the circuit breaker is open for effecting the closing thereof, and means controlled by said cooperating relay means when the control switch is opened while the circuit breaker is closed for effecting the opening thereof.

7. An anti-pump control arrangement for an automatic trip free circuit breaker comprising a plurality of cooperating relay means, a single throw stay-put control switch, means controlled jointly by said control switch and one of said plurality of relay means and dependent on the circuit controlling position of the circuit breaker for controlling the operation of another of said plurality of relay means, means controlled by said other relay means for effecting the closing of the circuit breaker, and means controlled jointly by said plurality of relay means and dependent on the circuit controlling position of the circuit breaker for effecting the opening thereof.

JUNIUS P. FRAPS.
